UNITED STATES PATENT OFFICE.

EDWARD SAMUEL, OF PHILADELPHIA, PENNSYLVANIA, ASSIGNOR TO WILLIAM WHARTON, JR., & COMPANY, INCORPORATED, OF SAME PLACE.

STREET-RAILWAY CROSSING.

SPECIFICATION forming part of Letters Patent No. 406,309, dated July 2, 1889.

Application filed September 21, 1888. Serial No. 285,979. (No model.)

To all whom it may concern:

Be it known that I, EDWARD SAMUEL, a citizen of the United States, and a resident of Philadelphia, Pennsylvania, have invented 5 certain Improvements in Street-Railway Crossings, of which the following is a specification.

My invention relates to improvements in the construction of street-railway crossings, 10 the main object of my invention being to so construct the crossing that cars traversing either track can pass the crossing without strain or jar, a further object being to facilitate the passage of wagons or other vehicles.

15 In the accompanying drawings, Figure 1 is a plan view of my improved street-railway crossing. Fig. 2 is an enlarged plan view of a portion of the crossing. Fig. 3 is a longitudinal section on the line 1 2, Fig. 2. Fig. 4 is a transverse section on the line 3 4, Fig. 2. Fig. 5 is a transverse section on the line 5 6, Fig. 2. Fig. 6 is a section on the line 7 8, Fig. 2. Fig. 7 is a detached perspective view 20 of a combined brace-bar and wagon-mount, forming part of the crossing structure. Fig. 8 is a plan view of a modification. Fig. 9 is a section on the line 9 10, Fig. 8; and Fig. 10 is a view of my improved crossing when used in connection with a conduit for cable or electric 25 railways.

30 A A are the main or continuous rails forming part of the crossing, and in the drawings I have shown these rails in the form of girder-rails of a peculiar cross-section; but it will be understood that any form of rail may be used. The rails A have treads *a*, for the wheels of the car, and wagon-treads *a'*, and said rails A A are supported in girders B B, crossing the rails at right angles or thereabout, depending upon the angle of the crossing. 35 These girders B have, outside of each of the rails A, grooved rail-sections *b*, and at the extreme ends of the girders are sockets *b'*, for the reception of the ends of the ordinary rails 40 of the street-railway.

45 Between the rails A A are two grooved rail-sections E E, forming continuations of the rail-sections *b*, and secured to the girder B in any suitable manner, bolts *e* and nuts *e'* being shown in the present instance for this

purpose. Depressions or pockets are formed in each girder B at the inner sides of the rails A A, and in each of these pockets rests a combined tie-bar and wagon-mount D, bolts *e* passing through the rail E, through the web 55 portion *d* of the tie-bar, and through the girder B, thus firmly securing the tie-bars to the girders and forming a quadrangular framework.

The tie-bar D has a longitudinal lip *d'*, 60 which overlaps the tread *a'* of the rail A, thus forming with the head of the rail a groove for the flange of the car-wheel, the lip portion *d'* of the tie-bar being slightly higher than the head *a* of the rail A. (See 65 Fig. 4.) The ends of the tie-bars D extend from the level of the treads *f* of the rails E to the wagon-treads *a'* of the rails A, thus forming a gradual incline by which wagon-wheels traversing the rails A can mount the crossing-rails and pass from rail to rail over the lips *d'*, thus avoiding the usual jar at street-railway crossings. The tie-bar D extends down 70 at the side of the rail, as shown in Fig. 6, to prevent the stones and ballast of the paving 75 sinking under the rails.

The rails A are continuous, as above remarked, and car-wheels traversing these rails will therefore freely pass the crossing without shock or jar, and the girders B are 80 formed in the following manner, to prevent jarring of the car, the wheels of which are traversing the crossing-track: The treads *g* of the outer rail-sections *b* of the girder are on a higher level than the treads *a* of the rails 85 A, so that a wheel traversing said rail-section *b* is lifted to such an extent that its flange will pass freely over the tread *a* of the rail A. The treads *f* of the rails E are also higher than the tread of the rail A to the extent of the depth of the flange of the car-wheel, so that after the flange of the wheel passes over the rail A the tread of the wheel 90 is in line with the tread *f* of the rail E, as shown by dotted lines in Fig. 3.

95 The girders B are supported in the center by bearing-blocks B', secured to the cross-tie in any suitable manner, and are preferably made in two pieces bolted together, as shown in Figs. 2 and 3, and each girder is by pref- 100

erence provided with an internal flange B^2 , which lies alongside of and re-enforces the inner flange of the rail-section E.

The treads of the rail-sections b may, if desired, be at the same level as the treads of the rails A, the bottoms of the grooves of the said rail-sections b being inclined so as to act upon the flanges of the wheels and lift said flanges to the level of the treads of the rails A and permit the passage of the flanges over said rails without shock or jar, as shown in Figs. 8 and 9. The girders B are shown in these figures as being in one piece supported in the center by blocks B'.

In Fig. 10 I have shown the girders B of my improved crossing made in two parts, leaving space for the slot w of a conduit W when used in connection with cable or electric railways.

When the crossing is used on double tracks, the section between the two tracks is level or similar to the part between the two rails of the one track.

I claim as my invention—

1. The combination, in a railway-crossing, of the unbroken rails A of the track, girders supporting said rails, and crossing-rails with tie-plates extending from girder to girder and forming wagon-mounts, all substantially as described.

2. The combination, in a railway-crossing, of the rails A of one track, transverse gird-

ers having cross-rails between the rails A, and tie-plates situated at the inner sides of the rails A, and having lips which overlap 35 said rails and are beveled to form a gradual rise, substantially as described.

3. The combination of the continuous main rails, the supporting-girders, the intervening cross-rail sections having high treads, and 40 the outer cross-rail sections having grooves with inclined bottoms for lifting the flanges of the wheels to the top of the main rails, all substantially as specified.

4. The combination, in a railway-crossing, 45 of the continuous main girder-rails and cross-rails, with plates situated at the inner sides of said main rails and extending below the base of the rail and alongside of the paving, substantially as and for the purpose described.

5. The combination, in a railway-crossing, of the main rails, the supporting-girders, the intervening cross-rail sections with internal 55 re-enforcing flanges B^2 on the said girders extending alongside the inner edge of the rail-sections, substantially as set forth.

In testimony whereof I have signed my name to this specification in the presence of two subscribing witnesses.

EDWD. SAMUEL.
